A. L. FLETCHER (NOW BY MARRIAGE A. L. WILSON)

FIRE ESCAPE

Filed Dec. 6, 1923

UNITED STATES PATENT OFFICE.

ANNA LAW FLETCHER, NOW BY MARRIAGE ANNA L. WILSON, OF SAN ANTONIO, TEXAS.

FIRE ESCAPE.

Application filed December 6, 1923. Serial No. 678,928.

To all whom it may concern:

Be it known that I, ANNA L. FLETCHER, a citizen of the United States, residing at San Antonio, in the county of Bexar and 5 State of Texas, have invented new and useful Improvements in Fire Escapes, of which the following is a specification.

This invention relates to fire escapes.

The object is to provide simple means for 10 the escape of persons from burning buildings, through the windows or other openings thereof, said means being easily and quickly applied in position at the bottom of a window to receive the persons to be lowered 15 in safety to the ground.

Another object is to provide a fire escape comprising a minimum number of parts, or elements that would get out of order and become inoperable at crucial moments during 20 the excitement attendant on the rescue of persons from such buildings.

A final object is to provide a relatively small, compact device of this character which may be detached and stored in small 25 space, either in the building or to be carried by the fire-fighting apparatus, the same having means whereby the occupants of the rescue car or basket may lower themselves to the ground, or be lowered by the firemen on 30 the ground, while at the same time the descent of said basket may be controlled by other firemen, who may also, as when the basket is full, guide the same outwardly and away from the wall of the building to prevent frantic persons in lower windows from 35 entering or endeavoring to enter the descending basket.

A full and complete understanding of the invention may be obtained from a consideration 40 of the following detailed description, taken in connection with the accompanying drawing forming a part of this specification, it being understood that while the drawing shows a practical form of the invention, the latter is not to be confined to strict conformity 45 with the showing thereof, but may be changed or modified, so long as such changes or modifications mark no material departure from the salient features of the invention, as 50 specifically pointed out in the appended claim.

In the drawings, in which similar reference characters designate corresponding parts throughout the several figures:

55 Figure 1 is a perspective view of the improved fire escape in use,

Figure 2 is a rear elevation of the basket and its connections with the guide cables or ropes and the hoisting cable.

Figure 3 is a top plan view of the same. 60

Figure 4 is a detail perspective of the hanger.

Referring to the drawing, there is shown a hanger 1 formed of a metal rod of a size and construction to withstand the relatively 65 great strain to which the same may be subjected in supporting the weight of one or more persons. At each end, the said rod is bent upwardly, as at 2, thence inwardly at right angles, as at 3, and the terminals 4 are 70 then bent downwardly to form hooks, spaced apart a distance to easily fit between the side members of a window frame 5 of the average dimensions.

The body portion 1 of the hanger is provided with a central eye 6 formed by turning the said rod downwardly into a circular loop, and at the points of intersection with the angularly bent, upstanding arms 2, the rod is similarly bent to form outer, spaced 80 eyes 7, as clearly illustrated in Figure 4 of the drawing.

When the hanger is applied in position, as shown in Figure 1, the downturned terminals 4 are adapted to bear against the inner face of the wall, while the arms 3 rest upon the window sill 8 and securely support the hanger in position to sustain the weight of the parts about to be described, as well as the weight of the persons being 90 rescued.

A car or basket 9 is adapted to be used in combination with the aforesaid hanger, and said basket may comprise any suitable form of receptacle mounted on any suitable kind 95 of frame to maintain the same in its proper form, that shown in the drawing being rectangular and comprising a rigid, metal frame (not shown) covered with some suitable, light, strong and durable fire-proof material, and having a front and a back wall, end walls and a bottom wall, the said bottom wall being preferably of rigid formation to stand the weight of the occupants of the basket.

The top and bottom frame members of the basket carry, on the rear side, upper and lower eyes 10 and 11 respectively, adjacent to the end walls of the basket, and the vertical pairs thus formed are in alinement with 110 each other and are spaced apart a distance equal to the distance between the eyes 7 of

the aforesaid hanger. The top frame member of said basket is further provided, on the rear side, with a centrally disposed eye 12, and it should be noted that the eyes 10, 5 11 and 12 carried by the basket are horizontally disposed, that is to say, they have vertically disposed passageways therethrough, while the eyes carried by the hanger are vertical with horizontal passageways.

10 Guide ropes or cables 13 are attached at one end to the eyes 7 of the hanger, and pass downwardly through the alined eyes 10 and 11 at each side edge of the basket and have their other ends reaching the ground.

15 A hoisting cable 14 has one end connected to the central eye 12 at the top of the rear side of the basket, and the said cable extends upwardly and is passed through the central eye 6 of the hanger, and is then passed down 20 to the ground, the length of said hoisting cable being necessarily enough to reach from the ground, when the basket is resting thereon, up to the hanger and down to the ground again, as will be understood.

25 Assuming that a building is equipped with the improved fire escape apparatus, it will be readily seen that the occupants of a room may easily and quickly apply the hanger in position on the window-sill as shown and described, and with the ropes or 30 cables already applied properly to the several eyes, the guide cables and the hoisting cable are allowed to fall to the ground. A fireman then grasps each of the guide cables 35 and holds the same rigidly to form guides for the basket to descend, while one or more firemen having hold of the hoisting cable, pays out the same, after the persons to be rescued have entered the basket.

40 The firemen or others holding the guide cables 13 may easily retard the downward movement of the basket under great load, if desired, by simply moving away from each other to cause said cables to bind in the 45 lower eyes 11 of the basket, as illustrated in Figures 1 and 2 of the drawing; and, in the event the basket is filled with persons to its capacity and the same is to be lowered down past other windows, in which there may be 50 other persons endeavoring to enter the same, the said firemen or others holding the guide cables may move away from the building so as to cause the basket to be out of reach as it is lowered.

After one load is safely on the ground, the 55 basket may be elevated again to the desired window, without changing the hanger, by means of the hoisting and lowering rope or cable, and the guides may be manipulated accordingly, as has been described. Should 60 persons be trapped in a room of a burning building and without the aid of a fire department or other help, they may attach the apparatus in position and lower themselves to the ground by means of the cable 14.

65 In the event the building is not equipped with such apparatus but the firemen are supplied with the same, the usual method of securing the escape in position is to fire some 70 sort of projectile into a window where entrapped persons are located, and by hauling in on an attached cord or rope, the device may be elevated to the window and applied in position, as before described.

75 From the foregoing it will be seen that a simple, cheaply manufactured, strong and durable fire escape apparatus has been provided, which may be easily applied in position for use and that persons may be easily 80 rescued thereby through the aid of firemen or others, and that it is comparatively easy for persons to successfully reach safety through their own efforts by the use of the device.

85 What is claimed is:—

In a fire escape, the combination with a hanger constructed of a single piece of metal and bent to provide hooks for attachment to the sill of a window, spaced end eyes, and a central eye, of a passenger-carrying basket 90 including a frame, pairs of vertically alined eyes carried at the rear side of the basket at the top and bottom thereof, guide cables suspended from the end eyes of the hanger and traversing the vertically alined eyes on the basket and extending to the ground, and a hoisting and lowering cable extending from the ground upwardly and through the central eye of the hanger and having its upper end connected to the top rail of the frame of the basket, said cables being adapted to be secured at their lower ends or to be held by hand and separated to act as a brake against the downward movement of the basket.

95 In testimony, that I claim the foregoing 100 as my own, I have hereto affixed my signature.

ANNA LAW FLETCHER.
